(57) **CLAIM**

The ornamental design for a sheet metal interconnect array, substantially as shown and described.

DESCRIPTION

FIG. 1 is a top view of sheet metal interconnect array and fixed on an environmental carrier structure in exemplary number of four.

FIG. 2 is a bottom view thereof.

FIG. 3 is a front view thereof.

FIG. 4 is a side view thereof; and,

FIG. 5 is a perspective view thereof.

The broken line showing of the environment is for illustrative purposes only and forms no part of the claimed design.
